WIRE-FEEDING AND RETRACTING APPARATUS

Harry J. Sketchley, Los Angeles, Calif.

Application February 15, 1946, Serial No. 647,794

5 Claims. (Cl. 15—104.3)

1

This invention relates generally to wire reels and more particularly to a wire reel especially suited for sewer cleaning apparatus.

It is common in cleaning sewers and other pipes to push a cleaning scraper or brush into the pipe by means of a stiff wire, simultaneously rotating the wire to rotate the brush attached thereto as it progresses along the interior of the pipe. It is also found practical to reciprocate the scraper or brush longitudinally for a short distance in the pipe wherever it engages a mass of material clogging the passage.

The feeding of the wire into the pipe has generally been accomplished by means of a reel mounted in a carriage which is in turn mounted in trunnions on an axis normal to the reel axis. One of these trunnions is made hollow in order to permit the wire to be fed from the reel, through the hollow trunnion and into the pipe. Thus the wire may be rotated in the pipe by rotating the revolvable carriage on its trunnions. In certain power driven reels, the reel may be driven to coil or uncoil the wire by means of gearing to which power is transmitted through a hollow sleeve passing through the hollow trunnion. In such machines the wire is fed out through the hollow sleeve and may be caused to simultaneously rotate by rotating the carriage in which the reel is mounted. The present invention presents a substantial improvement in such power driven reels mounted in rotating frames. These reels have in the past been subject to several limitations in their operations which it is the object of the present invention to overcome.

In the first place the rotation of either the frame, or reel, or both, subjects the wire coiled on the reel to a powerful centrifugal force which tends to cause the wire to leave the reel and become ensnared in the apparatus, particularly when wire is being uncoiled from the reel. Previously used reels carry hold-down clips which are opened at one point in each revolution by cam action to permit the uncoiling of the wire. These have proved complex to make and subject to failure in operation, however, and it is therefore an object of the present invention to provide a simple and rugged means for holding the wire onto the reel. This means consists of a cage enclosing the reel and mounted on the revolvable carriage, but not rotatable with the reel, and a set of rollers mounted in said cage parallel to the reel axis, and disposed about the periphery of the reel.

A second difficulty has arisen in attempting to

2

uncoil the wire and feed it forceably into clogged pipes by merely driving the reel. When the force resisting the outward feeding of the wire through the hollow trunnion becomes substantial, the wire uncoiled from the reel tends to bend or loop back upon itself and become entangled in the apparatus, rather than pass out of the rotating frame through the hollow trunnion. It is therefore the object of this invention to provide a positive means within the rotating frame which may be used to feed the wire out through the hollow trunnion without the danger of looping and entangling the wire. In the preferred embodiment described herein, this is accomplished by a set of feed rolls which may be controlled and driven to feed wire outwardly from the revolvable carriage through the hollow trunnion or may be reversed to retract the wire from the pipe. This method of retraction of the wire is very useful when it is desired to retract the cleaning tool only a slight distance from some obstruction within the pipe in the process of clearing it. For coiling up any considerable length of wire on the reel, however, it has been found preferable to drive the reel itself. In order to provide satisfactory selection, braking, and control for these two methods of driving the rolls, both trunnions in the preferred embodiment of the invention are made hollow, one being used to house a sleeve which drives both the reel and the wire feeding mechanism, and the other providing a passage for control means.

Another advantage of the sewer cleaning apparatus herein disclosed resides in the novel manner in which the revolvable carriage and the wire feed are independently driven. The wire feeding mechanism is preferably driven by a drive located near the hollow trunnion through which the wire is withdrawn from the revolvable carriage, and is driven by means of a hollow sleeve rotatably borne in the hollow trunnion. The revolvable carriage, however, is driven by means located at its opposite end near the second trunnion. This arrangement of the drive is especially advantageous in the larger sizes of truck transported sewer cleaners since it provides for driving the carriage with the minimum of shafting and for driving the wire feed with the minimum of equipment carried within the revolvable carriage.

Other advantages of the invention will be apparent from the description of a preferred embodiment of the invention shown in the drawings, in which:

Figure 1 is a plan view of an embodiment of the

invention mounted on a conventional truck frame;

Figure 2 is a side elevation of the invention, with some of the driving gear omitted for purposes of clarity;

Figure 3 is a schematic plan showing the reel and mechanism for driving it;

Figure 4 is a vertical longitudinal section of the trunnion located toward the forward end of the truck;

Figure 5 is a vertical longitudinal section of the rear trunnion;

Figure 6 is a vertical sectional view of the wire feeding mechanism as taken along the line 6—6 in Fig. 1 in the direction of the arrows;

Figure 7 is a second vertical sectional view of the wire feeding mechanism taken along the line 7—7 in Fig. 6;

Figure 8 is a partial plan view showing details of some of the control mechanism.

In the plan view, Fig. 1, the body of a truck is suggested by the dashed lines indicating longitudinal channel members 10 and the rear wheels 11.

For convenience in describing the illustrated embodiment of the invention the truck will be used as a frame of reference, "forward," "rear," "upper," "lower," "right," and "left" being used to designate the relative position of parts as shown on the truck, but it is to be understood that the invention is not limited to any particular type of support whether portable or permanent or to any particular position with respect to the horizontal.

On the body members 10 of the truck a heavy frame indicated generally by the numeral 12 is erected. In the side view of Fig. 2, it is revealed that this frame is built of steel channel members comprising a lower frame 13, several uprights 14 mounted thereon, and an upper frame 15, having a front transverse member 16 and a rear transverse member 16a.

A reel carriage 17 in the shape of rectangular frame is mounted by means of trunnion mounts 18 and 18a on members 16 and 16a to revolve within stationary frame 12 about a horizontal axis longitudinal with respect to the truck. A reel 19 is rotatably mounted within the carriage 17 in any convenient manner such as on a shaft 20 journalled in flange bearings 21 and 21a on the right and left side members of frame 17.

As mentioned, the carriage 17 is revolvable mounted about a horizontal longitudinal axis in the main frame 12 and reel 19 is mounted in carriage 17 for rotation about a transverse axis normal to the axis of rotation of carriage 17. Thus reel 19 may be rotated both about its axis and about a diameter coincidental with the axis of revolvable carriage 17.

As will be explained in detail hereinafter the reel 19 is adapted to hold a coil of wire 22, the uncoiled portion of which passes out of carriage 17, through a hollow bore in trunnion 18a. A suitable pipe-clearing tool (not shown) is fastened, to the free end of wire 22 so that rotation of the reel upon its axial shaft 20 will feed the wire 22 from, or wind it upon the reel 19, depending on the direction of rotation. The revolution of the reel carriage will rotate the wire 22 about its longitudinal axis for the purpose of transmitting rotary motion to said pipe-clearing tool as it is being advanced or retracted in the pipe being cleaned. For flexible operation of the apparatus, it is desirable that these two movements of reel 19 be independent of each other so that

they can be independently controlled. Furthermore, as previously explained, advancement of the wire 22 by merely rotating the reel 19 in an uncoiling direction tends to cause the wire to loop and become ensnared in the apparatus. It is therefore highly advisable to provide some positive means independent of reel 19 for advancing and retracting wire 22. The preferred form of the apparatus of the invention by which these functions are accomplished will now be described in detail.

The driving mechanism for reel, carriage and wire feed as shown in Fig. 1 may be seen with greater clarity in the schematic plan view of Fig. 3 from which structural details not involved in the driving mechanism have been omitted.

Suspended by brackets 23 (seen in Fig. 2) under the left forward corner of frame 12 is a bearing 24, supporting a power shaft 25, driven by some suitable source of power such as the engine of the truck upon which the preferred embodiment shown is mounted. Shaft 25 may be thrown into driving engagement with coaxially mounted sprocket 26 and variable speed transmission 27 by means of a clutch 28, manually operable by a lever 29.

Transmission 27 may be a "Reeves" drive type of transmission, or an ordinary automotive three-speed transmission, or any other type of transmission capable of giving a suitable range of speeds for the sprocket 30 shown mounted on the rear or power output end of transmission 27 in Fig. 3. Sprocket 30 drives a countershaft 31 mounted on the opposite (right) side of the truck and under the truck frame by means of chain 32 and a sprocket 33 on the rear end of countershaft 31. Countershaft 31 in turn drives by means of a forward sprocket 34 and chain 35, a sprocket 36 which comprises part of forward trunnion mounting 18, and provides the means for revolving carriage 17. The details of forward trunnion 18 are shown in the sectional view of Fig. 4. Sprocket 36 is seen to be rigidly bolted by bolts 37 to the forward portion of carriage 17, together with a tubular trunnion 38 and a brake drum 39. Tubular trunnion 38 is journaled in a bearing 40 mounted on the forward frame member 16. Brake drum 39 may be used to decelerate the rotational movement of carriage 17 by the application of any suitable brake shoe means (not shown). Passing through tubular trunnion 38 and concentric therewith are seen a rod 42 and tube 41 which are used for purposes of controlling the wire feed and reel driving mechanisms as explained hereinafter.

The means for transmitting power to the revolvable carriage having been described, attention is now directed to means for driving the reel and wire feed in Fig. 3. Sprocket 26 drives a countershaft 43 mounted on the right side of the truck and under the truck frame by means of a forward chain 44 and sprocket 45. Countershaft 43 is provided at its rear end with a sprocket 46 which transmits power by means of a chain 47 and a sprocket 48 to a suitable variable speed transmission 49 which is slung from the underside of the truck chassis near the left rear wheel.

Transmission 49 drives double clutch 50, operated manually by means of a handle 51, in order to drive either sprocket 52 or 53. A countershaft 54 is mounted on the underside of the truck chassis near the right rear wheel and is provided at one end with a gear 55 and near the other end 75 with a pair of sprockets 56 and 57. Sprocket 52,

5

when engaged by clutch 50, drives countershaft 54 by means of a chain 58 and a sprocket 59 on an intermediate shaft 60 mounted on the truck body, and a gear 61 on shaft 60 engaging gear 55. The introduction of the intermediate shaft 60 causes shaft 54 to be rotated in the direction which is the reverse of that of sprocket 52, and clutch 50. If it is desired to drive shaft 54 without any such reversal, clutch 50 is shifted to engage sprocket 53 which drives shaft 54 directly by means of a chain 62 and sprocket 56. The second sprocket 57 on shaft 54 transmits power to either the wire feed or the reel driving mechanism through a chain 63 and sprocket 64 mounted on trunnion mounting 18a in a manner to be described.

It is seen therefore that these mechanisms may be driven at a variety of speeds as selected by control of transmission 49 and may be driven directly or reversed in direction by the operation of clutch 50.

The details of trunnion mounting 18a are shown in the sectional view of Fig. 5. It is seen that wire 22 passes out of revolvable carriage 17 through a forwardly projecting tubular trunnion 65 rigidly bolted on the rear transverse channel member 16a of the stationary frame 12 and also through a bushing 66 passing through member 16a. A cylindrical sleeve 67 is rotatably borne on the trunnion 65 by means of anti-friction bearings 68. The rear end of reel carriage 17 is in turn rotatably borne on sleeve 67 by means of a pair of anti-friction ball bearings 69. Trunnion 65 thus remains stationary at all times and carriage 17 is free to be rotated by the carriage driving means at the forward end of the apparatus regardless of the direction or rate of rotation of sleeve 67, which thus provides a means for transmitting power from a source external to carriage 17 to the wire feed and the reel 19 supported within the carriage, even while the carriage is undergoing rotation. As previously explained, this power is delivered to sprocket 64 which is keyed to sleeve 67 so as to drive a second sprocket 70 mounted thereon within the revolvable carriage. A shaft 71 shown in Fig. 3 mounted within revolvable carriage 17 is driven by sprocket 70 by means of chain 72 and sprocket 73.

Shaft 71 carries a bevel gear 74 disposed to mesh with a second bevel gear 75 which is carried in a bearing 76 mounted on the housing 17 of a wire feed roll mechanism indicated generally by the numeral 78 and shown in detail in Figs. 6 and 7.

It is seen that bevel gear 75 is fastened to end of a short shaft 79 by a nut 80. Shaft 79 is journaled in a bearing 82 mounted on the inside surface of the housing 17 and is provided at its inner end with a pinion 83 which is keyed to shaft 79 by means of key 81. Pinion 83 meshes with two lower gears 84 and 85, which in turn mesh with two upper gears 86 and 87. The four gears 84, 85, 86, and 87, are mounted on four shafts 88, 89, 90, and 91, which are parallel with shaft 79 and are journaled at each end in bearings mounted on the inner surfaces of the side plates of housing 17 in a manner to be described. Mounted on the four shafts and rotating with the four gears, are four rolls 92, 93, 94, and 95, which are grooved at the periphery to receive wire 22.

Of the eight bearings required for the aforementioned shafts 88, 89, 90, and 91, the four lower bearings 96 for shafts 88 and 89 are fastened immovably to the side plates 17 but the upper

6

bearings 97 (for shafts 90 and 91) are provided with tongues 98 carried in grooved ways 99 projecting from the inner surfaces of side plates 17 so as to make upper bearings 97 slidably movable in a vertical direction as viewed in Figs. 6 and 7.

The four upper bearings 97 support four heavy coil springs 100, which in turn support a cover plate 101, which may be raised or lowered relative to the housing 17 by means of any conventional means such as toggle lever 102, which is connected to an anchoring rod 103 passing through cover plate 101 and provided at its lower end with an eye 103a. A bolt 104 passes transversely through housing 17 and eye 103a, the latter being positioned by spacer 105. Cover plate 101 is also provided at its four corners with four holes concentric with the four coil springs 100 and loosely receiving four vertical guide rods 106, which project upwardly from upper bearings 97 through the coil springs 100 and the aforesaid holes in the cover plate 101 to maintain the springs and plate in suitable alignment. It is seen that when toggle 102 is thrown into the position illustrated in Figs. 6 and 7, cover plate 101 is displaced downwardly and upper bearings 97 are urged downwardly by springs 100. Grooved pulleys 94 and 95 are thus resiliently urged into contact with wire 22 and gears 86 and 87 into mesh with gears 84 and 85 respectively.

When, however, toggle 102 is shifted into an opposite position so as to raise cover plate 101, upper bearings 97 are raised a slight distance, pulleys 94 and 95 cease to engage wire 22. Gears 86 and 87 are never completely out of mesh with their driving gears 84 and 85, but the wire 22 ceases to be driven by the feed rolls.

Since the wire feed mechanism 78 can be driven in either direction it can be conveniently used for retracting wire 22 as well as for feeding it out and it is frequently advantageous to so use it when retracting the wire only a short distance in the process of clearing some obstacle from a pipe or sewer. When, however, it is necessary to retract and wind on reel 19 a considerable length of wire 22, it is preferable to pull the wire by rotating reel 19, since attempting to push the wire 22 onto the reel 19 by the feed rolls tends to result in ensnarling it. Power for driving reel 19 is transmitted from shaft 71 by means of a clutch 107, at its forward end, to a second shaft 108 which drives a third shaft 109 through spur gears 110 and 111. The forward end of shaft 109 is provided with a beveled pinion 112 which is disposed so as to mesh with a beveled ring gear 113 carried by reel 19.

Clutch 107 is operated by means of a handle 114 and serves as a means for engaging or disengaging the reel driving shafting from the power shaft 71.

Since the heavy weight of the reel 19 and the wire 22 carried thereon gives it considerable momentum when in motion, a brake 115 is provided on shaft 108 for slowing or stopping the movement of reel 19.

The feed mechanism 78, clutch 107 and brake 115 may be operated manually if the revolvable carriage 17 is allowed to remain stationary whenever the wire 22 is advanced or retracted. If desired, however, these three devices may be controlled even while the carriage 17 is being revolved by providing the apparatus with the remote control means illustrated in Fig. 3. Brake 115 may be operated by means of a rod 41 passing through the center of forward trunnion

mount 18 as seen in Fig. 4. Also passing through trunnion mount 18 is a short section of tubing 42 which slips freely in trunnion 38 and over rod 41 and at its rearward end operates a lever 116 which pivots about a hinge 117 mounted on revolvable carriage 17. Lever 116 operates a rod 118a which is connected to the wire feed mechanism handle 102 and also to the reel drive clutch handle 114. When tube 42 is displaced axially a short distance in one direction, it causes clutch 107 to be engaged and to drive reel 19 and at the same time operates to raise the upper wire feed rolls 94 and 95 from the wire 22, thereby permitting its free retraction from the pipe as it is wound on the reel. If, on the other hand, tube 42 is displaced axially a slight distance in the opposite direction, clutch 107 is disengaged and upper wire feed rolls 94 and 95 are lowered into driving contact with wire 22 and may then be employed to feed or retract said wire 22 in a manner controlled by the manipulation of the reversible clutch 50.

One feature of the sewer or pipe cleaning device remains to be described, namely, the means employed for retaining the wire 22 on reel 19 against the centrifugal force tending to throw it off while the carriage 17 is being revolved. Instead of the complicated devices used in the prior art and carried on the reel itself, the device herein disclosed employs rollers 118 (seen in Fig. 2) mounted substantially normal to the plane of the reel and disposed about its periphery to hold wire 22 in place. These rolls are carried in a framework 120 which is a rigid extension of carriage 17 and rotates about the longitudinal axis thereof but not about the transverse axis of reel 19. It is frequently desirable to guide wire 22 in other parts of the apparatus as by passing it between a pair of rollers 121 mounted in the carriage 19 to guide the wire from the reel to the wire feed mechanism.

Referring to Figure 8, I have shown the details of the control means for releasing or applying the pressure of the rolls on the wire or rod 22 and concurrently therewith engaging or disengaging the split clutch 107. The rolls 95 are held in frictional engagement with the cable 22 by means of springs 100. The springs 100 are urged downwardly by means of a plate 101. The plate 101 is formed with an aperture 125 adapted to receive the rod 103. A collar 126 is secured adjacent the top of the rod 103 by means of a lock nut assembly 127. A lever arm 128 is pivotally secured to the collar 126 by means of a pin 129 and is pivotally connected to the link 102, thereby forming a toggle link relation.

It would be apparent that rotation of the lever 128 clockwise or counter-clockwise would tend to cause upward or downward movement of the plate 101. A connecting rod 130 is secured at one end thereof to the lever 128 and at the other end thereof to a bell crank 131. The bell crank 131 is operatively associated with a second bell crank 132 by means of the ball-and-socket assembly 132.

The bell crank 132 has one arm connected to a connecting rod 135 which said rod is also connected to the lever 114 so that rotation of the bell crank 132 will cause shifting of the lever 114 and, therefore, engagement or disengagement of the split clutch 107.

The bell crank 132 is also connected by means of a rod 137 to a bell crank 138. The rod 118a is connected to the bell crank 138 so that longitudinal displacement of the rod 118a causes

longitudinal displacement of the rod 137 and, therefore, rotation of the bell crank 132.

Thus it will readily be seen that movement of the rod 118a to the left in Figure 8 causes a clockwise rotation of the bell crank 132 and, hence, engagement of the two halves of the split clutch 107. Such clockwise direction of the bell crank 132 simultaneously causes counter-clockwise motion of the bell crank 131 and a counter-clockwise motion of the lever 128 sufficient to raise the plate 101 from pressure engagement with the springs 100 to release the pressure on the rolls 95.

In Figure 4 I have shown a handle 140 pivotally connected to the sleeve 42 so that pivotal motion of the handle 140 causes longitudinal movement of the sleeve 42, thereby shifting the lever 116 either to the right or left depending upon the motion of the handle 140. It will, therefore, be apparent that rotation of the handle 140 in a counter-clockwise direction will bring about the result above described with respect to the engagement of the clutch 107 and the disengagement of the pressure of the feed rolls against the cable 22.

As previously explained, the sleeve 42 has a rod 41 extending axially therethrough, the rod 41 being associated with the brake assembly 115 adapted to control free wheeling of the reel 19. A lever 142 is pivotally connected to the rod 41 so that rotation of the lever 142 in a clockwise direction releases the brake 115 and in a counter-clockwise direction engages the brake 115.

In operation, a scraper or brush is attached to the free end of wire 22 and inserted in the open end of the pipe to be cleaned, the truck engine is started, the desired carriage speed is selected by means of transmission 27, the desired wire feed speed is selected on transmission 49, and clutch handle 29 is thrown to place the apparatus in motion. Carriage 17 begins to revolve, but no feeding of the wire occurs until clutch 50 is shifted into a driving position. When it is desired to feed out wire 22 from the reel 19, brake 115 and clutch 107 are disengaged and handle 102 is thrown into a position which lowers upper feed rolls 94 and 95 to contact wire 22 and feed it from the apparatus. The rotational velocity of reel 19 is readily checked, when desired, by means of brake 115.

When it is desired to retract the wire after completion of a pipe cleaning job, handle 102 is thrown into an opposite position and, if this is done by means of remote control rod 118a, clutch 107 is simultaneously engaged and reel 19 begins to turn in a direction to coil up wire 22.

It is to be understood that the forms of my invention shown are merely illustrative of the principles involved and are not to be taken as limiting the scope thereof to the details shown.

For instance, the various equipment borne by revolvable carriage 17 need not be carried within the carriage frame but may if desired be attached to the outer surfaces of the carriage framework. Also, gearing, V-belts and pulleys, or other driving means may be substituted for the chains and sprockets. The clutches, braking means, and transmissions may be altered as to type and as to position without departing from the scope of the invention. It should further be noted that the invention presents a substantial advancement over prior art in that rotating controls are used throughout the apparatus in order to make it unnecessary to bring the machine to a stop when it is desired to change direction of feed of the

wire, to increase or decrease feed, or to retard the rotation of the reel.

What I claim as my invention and desire to secure by Letters Patent is:

1. In an apparatus for paying out a flexible shaft or wire from a reel and rotating said wire, the combination of: a supporting frame; a reel-carrying carriage journaled in said frame by means of a first tubular bearing and a second bearing; a reel rotatably mounted in said carriage; a first pulley means rotatably mounted at said tubular bearing; a pair of rollers rotatably mounted in said carriage and adapted to pay out or momentarily retract said wire from said reel through said tubular bearing; power transmission means for transmitting power from said first pulley means to both of said rollers and adapted to drive them cooperatively in either direction; a reversible power means mounted in said frame and adapted to drive said first pulley means in either direction; a second pulley means located at said second bearing in non-rotational engagement with said carriage and power means associated therewith adapted to cause rotation of said carriage.

2. In an apparatus for paying out a flexible shaft or wire from a reel and rotating said wire, the combination of: a supporting frame; a reel-carrying carriage journaled in said frame by means of a pair of bearings, one of which is tubular; a reel rotatably mounted in said carriage; a first pulley means rotatably mounted at said tubular bearing; a pair of rollers rotatably mounted in said carriage and adapted to pay out or momentarily retract said wire from said reel through said tubular bearing; power transmission means for transmitting power from said first pulley means to both of said rollers and adapted to drive them cooperatively in either direction; a reversible power means mounted in said frame and adapted to drive said first pulley means in either direction; a second pulley means located at one of said bearings in non-rotational engagement with said carriage and power means associated therewith adapted to cause rotation of said carriage.

3. In an apparatus for paying out a flexible shaft or wire from a reel and rotating said wire, the combination of: a supporting frame; a reel-carrying carriage journaled in said frame by means of a pair of bearings, one of which is tubular; a reel rotatably mounted in said carriage; a first pulley means rotatably mounted at said tubular bearing; a pair of rollers rotatably mounted in said carriage and adapted to pay out said wire from said reel through said tubular bearing; power transmission means for transmitting power from said first pulley means to both of said rollers and adapted to drive them cooperatively and to said reel for driving it alternately with said rollers; a reversible power means mounted in said frame and adapted to drive said first pulley means in either direction; a second pulley means located at one of said bearings in non-rotational engagement with said carriage; and power means associated therewith adapted to cause rotation of said carriage.

4. In an apparatus for paying out a flexible shaft or wire from a reel and rotating said wire, the combination of: a supporting frame; a reel-carrying carriage journaled in said frame by means of a pair of trunnions, one of which is a stationary tubular shaft projecting into said carriage from said supporting frame; a reel rotatably mounted in said carriage; a rotatable sleeve surrounding said stationary tubular shaft and rotatable with respect to said carriage; a first pulley means mounted on said sleeve external to said carriage; a second pulley means mounted on said sleeve within said rotating carriage; a pair of rollers rotatably mounted in said carriage and adapted to pay out said wire from said reel through said tubular trunnion; power transmission means for transmitting power from said second pulley means to both of said rollers and adapted to drive them cooperatively and to said reel for driving it alternately with said rollers; a reversible power means mounted in said frame and adapted to drive said first pulley means in either direction; a third pulley means non-rotatably associated with said carriage; and power means associated therewith adapted to cause rotation of said carriage.

5. In an apparatus for paying out a flexible shaft or wire from a reel and rotating said wire, the combination of: a supporting frame; a reel-carrying carriage journaled in said frame by means of a first tubular bearing and a second tubular bearing; a reel rotatably mounted in said carriage; a first pulley means rotatably mounted at said first tubular bearing; a pair of rollers rotatably mounted in said carriage and adapted to pay out said wire from said reel through said first tubular bearing; power transmission means for transmitting power from said first pulley means to both of said rollers and adapted to drive them cooperatively and to said reel for driving it alternately with said rollers; a control means passing through said second tubular bearing and adapted selectively to couple either said reel or said rollers to said power transmission means; a reversible power means mounted in said frame and adapted to drive said first pulley means in either direction; a second pulley means in non-rotational engagement and co-axial with said carriage; and power means associated therewith adapted to cause rotation of said carriage.

HARRY J. SKETCHLEY.
